CLEAN-OUT PLUG FOR DRAINPIPES

Emmett E. Lally and Theodore G. Lally,
Denver, Colo.

Application December 12, 1949, Serial No. 132,612

2 Claims. (Cl. 4—255)

1

This invention relates to improvements in clean out devices for plumbing drains or the like.

It is common practice to provide clean out plugs in certain pipes which drain waste to the sewer, these plugs being removable to permit insertion of a cleaning snake, or other cleaning device, for removing obstructions in the drain pipes. The conventional clean out plug must be completely removed from the drain pipe before any substantial draining of an accumulation of water and waste, which may have built up above the plug, may occur. If the latter condition prevails, and the clean out plug be removed, the water and waste above the plug will flow through the plug receiving opening, and, if not caught by a suitable receptacle, produces not only an untidy condition, but may cause damage to the building by reason of loosening of wall plaster, etc., which the water may contact.

One of the objects of this invention is to provide a clean out device with a valve therein which may control bleeding of any liquid thereabove prior to complete removal of the clean out plug from the pipe.

Another object is to provide the device with a drain spout which eliminates any running of liquid downwardly along the drain pipe.

Another object is to provide the device with agitator means for breaking up an accumulation of semi-solid waste, which may build up in the clean out device or in the pipe adjacent thereto, to which the device is attached.

Another object is to provide a clean out device with a plug which may be operated to determine the presence of water thereabove, without completely removing the plug from the device.

Another object is to construct the plug of the clean out device with suitable lug means which may be struck with a hammer to tighten or loosen the plug.

Another object is to provide the plug and valve seat associated therewith with ground seats, thus eliminating gaskets or other unsafe seals.

Another object is to construct the device in such manner that installation requirements are no greater than those for conventional clean out plugs.

A further object is to construct the device so that it may be installed in any type of pipe.

Still further objects, advantages, and salient features will become more apparent from the description to follow, the appended claims, and the accompanying drawing, in which:

Figure 1 is a side elevation of a portion of a

2

piping system connected to a sewer, or the like;

Figure 2 is an enlarged fragmentary side elevation of Figure 1;

Figure 3 is an enlarged end elevation taken in the direction of arrow 3, Figure 2;

Figure 4 is a section taken on line 4—4, Figure 3; and

Figure 5 is an end elevation taken in the direction of arrow 5, Figure 4.

10 Referring in detail to the drawing, and particularly Figure 1, a drain pipe 10 has its upper end connected to a sink, or other means for receiving drain water and waste, its lower end being adapted to connect with a sewer, and having interposed therein, if desired, a grease trap 12. The clean out device 13 may be interposed between the ends of the drain pipe at any desired point therein.

The clean out device comprises a tubular valve body 14 having means at one end thereof, illustrated as male threads 15, for securing it to a T pipe fitting 16. The valve body is provided with female threads 17 at its other end which receive the male threads on a plug 18. The 25 valve body and plug are provided with tapered cooperating valve seats 19, 20, respectively, which prevent liquid from flowing through the valve body when they are engaged, as shown in Figure 4.

The valve body is provided with a tubular drain spout 21 which forms a bleed port and permits liquid to drain through it when the valve seats are separated, as will be apparent from Figure 4, the spout being preferably disposed downwardly.

30 The plug is provided with lugs 22, which may be struck at their radially disposed sides 23, with a hammer or other impact tool, for tightening or loosening the plug from the valve body.

The plug is also provided with a pair of tongues 24 which are bent over the bight of a U-shaped agitator member 26, the tongues fitting the bight loosely so that the agitator member may move freely within the bore of the valve body 14 and strike the inner walls thereof 45 during rotation of the plug and agitator relative to the valve body. A plurality of elongated angularly spaced ribs 27 are also provided on the wall of the bore which tend to prevent rotation of the accumulation of foreign matter collected in the tubular member and thus aid the agitator member in loosening any foreign matter in the clean out device or the pipe to which it is attached. The legs of the U-shaped agitator 50 may be of a length to extend any desired dis-

Figure 1 is a side elevation of a portion of a

tance within T 16 for loosening any accumulation of foreign matter therein and have therefore been shown broken in Fig. 4.

Assuming that the drain pipe has become completely clogged at a point below the clean out device and a column of water is contained in the pipe above the device, a receptacle is placed below spout 21 and the plug 18 loosened sufficiently to permit the water above the device to drain or bleed therefrom. After flow ceases the plug is completely removed and the drain pipe cleaned in the usual manner with a snake or the like, as well known in the art, the open valve body providing access to the drain pipe. Since the lower edge 28 of the spout is below any part of the valve body, it will be apparent that any dripping from the spout will occur at this point, thus preventing any of the water from running down the outer surface of the drain pipe.

The lugs 22 expedite tightening and loosening the plug where the device is disposed in a position where quarters are close and there is insufficient space to swing a pipe wrench or other wrench, but sufficient space to move an impact tool, such as a hammer. It is to be understood, however, that any type of wrench engaging means may be employed on the plug in lieu of the lugs.

While threads have been illustrated as the means for securing the device to a drain pipe, it will be understood that this is exemplary only. For example, if the drain device were to be installed in a bell and spigot fitting, the portion which contains the threads would be made cylindrical and the device secured by caulking; for copper fittings a sweat joint would be employed; for lead waste pipe a solder wipe joint would be employed; and if the installation required special threads, a flange, etc., the end which is shown with threads 15 is merely modified to render it adaptable for connection to the particular drain pipe.

While the device has been illustrated disposed in a horizontal position in a vertical drain pipe, it is apparent that it may be disposed in a vertical position, such as at the bottom of a grease trap or the like, the spout 21 still remaining in a downwardly ranging direction.

Many modifications will become apparent within the purview of the invention and the specific device disclosed is, therefore, to be regarded as exemplary only, and the invention not limited thereto, except as defined by the scope of the appended claims.

Having described the invention, what we claim as new is:

1. A clean out device for a drain pipe having a fitting with a threaded opening in one side thereof, a tubular body having one end provided with a male thread engageable in the threaded opening, and a female thread in the other end, an annular valve seat on the inside of the tubular body intermediate its ends facing the female threads, a plug having a male thread engageable with the last named female thread and an annular valve surface engageable with the valve seat, the tubular body having a drain spout provided with a bleed port downstream from the valve seat, adapted to be put into communication with the drain pipe when the plug is moved outwardly away from the valve seat, the inner end of the plug having a cup-like cavity provided in its bottom with two spaced bendable fingers, and a two pronged U-shaped agitator positioned with its base in said cavity and moveably attached to the plug by said fingers, the prongs projecting beyond the end of the plug and into the tubular body for breaking up material collected therein when the plug is rotated relative to said body, the plug being removable from the tubular body upon further rotation thereof to provide access to the drain pipe for inserting a snake or the like.
2. A device in accordance with claim 1, in which the inner surface of said tubular body has a plurality of circumferentially spaced ribs extending longitudinally to resist rotation of material collected therein when the plug and agitators are rotated to open the bleed port.
